(57) **CLAIM**

The ornamental design for a furniture fastening bow, as shown and described.

DESCRIPTION

FIG. 1 is a front-right-top perspective view of a furniture fastening bow showing my new design.

FIG. 2 is right side elevational view thereof. The left side elevational view is a mirror image of the right side elevational view.

FIG. 3 is a front elevational view thereof.

FIG. 4 is a rear elevational view thereof.

FIG. 5 is a top plan view thereof.

FIG. 6 is a bottom plan view thereof.

FIG. 7 is a rear-left-top perspective view thereof.

FIG. 8 is a bottom-left-front perspective view thereof; and, FIG. 9 is bottom-rear-right side perspective view thereof.

1 Claim, 9 Drawing Sheets

FIG. 2

FIG. 3
